UNITED STATES PATENT OFFICE

CHARLES E. FRIESNER, OF TOLEDO, OHIO, ASSIGNOR TO THE HETTRICK MANUFACTURING COMPANY, OF TOLEDO, OHIO, A CORPORATION OF OHIO

MOUNTING FOR WALL TENTS

Application filed August 27, 1931. Serial No. 559,615.

This invention relates to tents, and an object is to produce a simple and efficient support for a tent so that the same may be quickly and conveniently erected or taken down and compacted in a relatively small space.

For purposes of illustration, but not of limitation, an embodiment of the invention is shown on the accompanying drawings, in which—

10 Figure 1 is a perspective view of a tent showing one of the supports therefor. Fig. 2 is an enlarged view showing the pole clamp. Fig. 3 is a transverse section on the line 3—3 of Fig. 2, and Fig. 4 is a transverse section on the line 4—4 of Fig. 2.

An illustrated embodiment of the invention comprises a wall tent having side and top walls 10 held taut in the usual manner by guy-ropes 11. For supporting the tent in upright position, a ridge pole (not shown) is supported by a pair of end poles 11. Each end pole 11 consists of telescoping rods 11^a and 11^b, the rod 11^a having a portion extending within the rod 11^b. These rods may be 25 any suitable shape, but in the present instance are tubular and may be of cast iron piping.

30 Encircling the outer end of the tubular rod 11^b is a collar 12 having outwardly projecting ends 13 which receive a bolt 14 having a nut 15. Disposed between the projecting ends 13 and securely clamped in place is the lower end of a post 16, which extends outwardly 35 from the end of the rod 11^b in substantially parallel relationship thereto. It is to be understood that the bolt 14 provides a pivot for the post 16, so that it may be swung against the post 11^b for convenience in transportation and packing. The post 16 may 40 be of wire and formed on the outer end thereof is an eye 17 which engages in an opening 45 formed in a catch 19.

The catch 19 is of sheet metal, provided 45 with an aperture 20 slightly larger than the circumference of the rod 11^a. Adjacent the opening 18, the aperture 20, as indicated at 50 21, is rounded to fit the rod 11^a and diametrically opposed to this surface is an arcuately shaped gripping surface 22, which is rounded to correspond to the curvature of the rod

11^a and is adapted to retain the rod in adjusted position, as will hereinafter appear.

Normally, the plate 19 is in inclined position, as shown in Fig. 2, and movement of the rod 11^a in a direction toward the rod 11^b 55 is prevented due to the frictional engagement between the opposed surfaces 21 and 22 of the catch 19. The greater the force exerted upon the rod 11^a in the direction indicated, the greater will be the binding action of the 60 gripping surfaces against the outside of the rod.

It is manifest that the telescoping rods efficiently retain the tent in erect position, and liability of the tent collapsing due to 65 telescoping of the rods is prevented. When it is desired to take the tent down, the plate 19 is lifted or moved upwardly slightly, which movement releases the rod 11^a and allows it to drop within the rod 11^b. Until the 70 catch 19 is lifted, however, telescoping movement of the rods relative to each other is prevented.

The above described construction may be 75 inexpensively manufactured and is of material advantage in eliminating the use of the ordinary wooden poles which are cumbersome to carry and difficult to erect and take down. The present construction enables the tents to be erected within a minimum of time, and, 80 inasmuch as the poles may be telescoped, they may be transported conveniently and occupy a minimum of space.

It is to be understood that changes in details of construction and arrangement may 85 be effected without departing from the spirit of the invention as defined in the appended claim.

What I claim as new and desire to secure 90 by Letters Patent is:

A fastener for telescoping tent poles or the like comprising a link pivotally secured at one end to the outer section and having its free end extending beyond the end of said section, a plate apertured to receive the inner section, a relatively loose pivotal connection between said plate and said link, a gripping edge on said plate adjacent said pivotal connection for frictionally engaging said inner section, and an inwardly extending lug hav- 95 100

ing a relatively small gripping edge on said plate diametrically opposed to said first edge for gripping the opposite side of said inner section, the walls of said aperture intermediate the gripping edges being spaced from said inner section.

10 In testimony whereof I have hereunto signed my name to this specification.

CHARLES E. FRIESNER.
